UNITED STATES PATENT OFFICE.

EVERETT T. PACKARD, OF AVON, MASSACHUSETTS.

RUBBER HEEL.

1,199,817.

Specification of Letters Patent.

Patented Oct. 3, 1916.

Application filed August 14, 1915. Serial No. 45,462.

To all whom it may concern:

Be it known that I, EVERETT T. PACKARD, a citizen of the United States, residing at Avon, in the county of Norfolk, in the State of Massachusetts, have invented a certain new and useful Improvement in Rubber Heels, of which the following is a specification, reference being had to the accompanying drawings.

- 10 The immediate object of this invention is to provide an inexpensive, but particularly serviceable spring heel in which special provision is made for reinforcing the heel, and for preventing the undue wearing of the rubber at the several points where the nails pass through the heel as well as for preventing the undue lateral deflection, or stretch, of the rubber when the heel is in service, as I will explain more fully hereinafter.
- 20 A heel embodying my present improvements is illustrated in and by the annexed drawings, Figures 1 and 2 showing, respectively, bottom and side views of the same. Fig. 3 is a transverse sectional view of said heel taken on the line 3—3 of Fig. 2. In Fig. 4 I have illustrated, by plan and edge views, one of a pair of reinforcing plates which I embed in the rubber heel at the time the latter is molded.
- 30 Referring to these drawings the letter *a* indicates the heel proper, the same being formed mainly of vulcanized rubber, and being of any approved size and style. In the process of making the said heel I place in the mold a pair of reinforcing plates *b—c* made of stiff material, such as sheet metal, said plates conforming in shape (when in their operative positions in the heel) to the sides and curved rear portion 40 of the heel as is best seen in Fig. 3 of the

drawings. Each of said plates is provided with a plurality of holes *d* which are of such size and so positioned that they may receive nails by means of which the heel may be fastened to the shoe, and the rear end portion of said plates overlap each other (see Fig. 3) so that when a nail is passed therethrough the two plates are, in effect, hinged together and are thus prevented from displacement with respect to each other. Said 50 plates are also formed with relatively larger holes *e* which fill with the plastic rubber mass; when the heel is being molded and, when the rubber has been vulcanized, the rubber in the several holes *e* serves to connect the rubber on the opposite sides of the plates *b—c* and to thus prevent the plates from working loose.

The bottom face of the heel is spotted as at *d'* in the operation of molding said heel, 60 the said spots being suitably positioned to register with the openings *d* in the concealed plates and so that, when nails are driven into the heel at the spotted points, said nails will pass through the said plate openings *d*. 65 The plates then operate to reinforce and strengthen the heel and to prevent it from lateral deflection in any direction. My described reinforcing plates add but little to the cost of heels of this class yet they effectively stiffen such heels and add materially to their serviceability.

Having thus described my invention, I claim as new and wish to secure by Letters Patent:

A rubber heel having embedded therein reinforcing plates that are hinged together at their rear end portions.

EVERETT T. PACKARD.
